Attorney

UNITED STATES PATENT OFFICE.

HENRY NELSON, OF ALBERT LEA, MINNESOTA.

FASTENING DEVICE.

1,257,517.

Specification of Letters Patent. Patented Feb. 26, 1918.

Application filed May 7, 1917. Serial No. 166,964.

To all whom it may concern:

Be it known that I, HENRY NELSON, citizen of the United States, residing at Albert Lea, in the county of Freeborn and State of Minnesota, have invented certain new and useful Improvements in Fastening Devices, of which the following is a specification, reference being had to the accompanying drawings.

10 This invention relates to certain improvements in fastening devices, and has relation more particularly to a device of this general character especially designed and adapted for use in maintaining in applied position 15 the closure members of jars or other containers.

It is an object of the invention to provide a novel and improved device of this general character whereby a closure member may be 20 readily and effectively maintained in operative position.

It is also an object of the invention to provide a device of this general character having novel and improved means whereby 25 the same affords a means for conveniently transporting the jar or other container to which the device may be applied.

The invention also has for an object to provide a novel and improved device of this 30 general character which is separable from the jar or other container and from the closure member, so that it is possible to effectively cleanse the jar or other container, the closure member and the fastening device so 35 that the same may be thoroughly cleansed and maintained sanitary.

The invention consists in the details of construction and in the combination and arrangement of the several parts of my improved 40 fastening device whereby certain important advantages are attained and the device is rendered simpler, less expensive and otherwise more convenient and advantageous for use, all as will be hereinafter 45 more fully set forth.

The novel features of the invention will hereinafter be definitely claimed.

In order that my invention may be the better understood, I will now proceed to describe the same with reference to the accompanying drawings; wherein

Figure 1 is an elevational view illustrating the fastening device constructed in accordance with the embodiment of my invention, in applied position;

Fig. 2 is an elevational view taken sub-

stantially at right angles to that in Fig. 1, illustrating my improved device in operative position;

Fig. 3 is a view in perspective of the 60 clamping jaws as herein included;

Fig. 4 is a view in perspective of the lever member as herein embodied;

Fig. 5 is a view in perspective of the yoke member and coacting hand-grasp as herein 65 included; and Fig. 6 is a detail sectional view showing a modified form of closure member.

As disclosed in the accompanying drawings, J denotes a jar or container of the 70 conventional type and provided adjacent its upper or open end with an annular shoulder 1, herein disclosed as afforded by an annular peripheral groove. C denotes a closure member adapted to coact in the conventional 75 manner with the open end of the jar J or the like. The closure member may be imperforate for the purpose of sealing the jar, or if preferred, as indicated in Fig. 6, wherein the central portion of the closure member 80 C' constitutes a wire mesh of predetermined gage but of sufficient fineness to prevent ingress within the jar or the like of insects or other foreign matter which would otherwise pollute the contents of the jar or container. 85

My improved fastening device is preferably formed of wire, and as herein disclosed the clamping jaws A adapted to be clamped upon the jar J or other container are produced from a single length of material. 90 The jaws A are substantially semicircular in form and a portion of the material midway of the jaws A is bent upon itself to afford a depending eye 2, while the opposite 95 end portions of the jaws are provided with eyes 3.

L denotes a lever member coacting with the jaws A to cause the same to have the requisite engagement with the jar J or other 100 container, below the annular shoulder 1. The lever member L is preferably formed of a single length of material and has one end provided with an inwardly disposed hook member 4, disposed through the eye 105 2 to effect a pivotal engagement. At a predetermined point inwardly of the hook member 4 the material comprised in the lever is coiled or returned upon itself to afford an eye 5. The opposite end portion of 110 the lever L is bent into substantially an L shape, with the heel portion 7 thereof formed

into substantially a semi-loop, in which an eye 3 is seated and through which eye a side portion of the semi-loop is directed. The arm 6 of the substantially L shape portion 5 of the lever member L constitutes a terminal of the lever member L and is provided at its free end portion with an eye 8 interlocked with the second eye member 3. The outer terminal of the second arm 9 is returned 10 to form an eye 10. The intermediate portion of the lever L, or that portion arranged between the eyes 5 and 10, is angularly related to the arm 9 at one side of the lever member L, and to the opposite end 15 portion 11 of the lever member L intermediate the eye 5 and the hook member 4.

By this arrangement it will be perceived that when the intermediate portion of the lever member L is forced inwardly into contact with the jar J or other container, the jaws A will be effectively clamped around said jar or the like at a point below the angular shoulder. It is also to be noted that the end portions 9 and 11 will be thrown 25 beyond the vertical, whereby the clamping engagement of the jaws A with the jar J or the like is maintained until the intermediate portion of the lever member L is thrown upward or outward.

30 B denotes a yoke member substantially U shape in form and having the free terminals of its side members pivotally engaged, as at 12, with the eyes 5 and 10. The intermediate portion 14 of the yoke member B is 35 adapted to overlie the closure member C or C' when the same is applied to the jar J or other container, and when the intermediate portion of the lever member is forced downwardly or in the direction toward the 40 jar J, the yoke member B will be caused to effectively clamp or hold said closure member C or C' in applied position, as is believed to be clearly apparent to those skilled in the art to which my invention appertains.

45 I also have found it of importance to return the opposite end portions of the intermediate portion 14 of the yoke member B to afford the longitudinally spaced eyes 15, with which are pivotally engaged, as at 16, 50 the terminals of the handle or hand-grasp 17, herein disclosed as substantially U shape in form. Through the medium of the handle or hand-grasp 17, it will be apparent, the jar or other container to which my improved fastening device may be applied, can 55 be transported or carried with convenience and facility and with the assurance of the fastening device being maintained in requisite coöperation with the jar J or other container and the closure member C or C'.

60 The manner of applying or removing my improved fastening device is believed to be readily understood, and it is also thought to be self-evident that, as my improved 65 fastening device is separable from the jar

J or other container and the closure member therefor, the jar or other container, the closure member, and the fastening device may be readily and conveniently cleansed in order to maintain the several members sanitary.

70 From the foregoing description, it is thought to be obvious that a fastening device constructed in accordance with my invention is of an extremely simple and comparatively inexpensive nature and is particularly well adapted for use by reason of the convenience and facility with which it may be assembled, and it will also be obvious that my invention is susceptible of some 80 change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A fastening device of the character described comprising coacting jaws formed from a single length of material and provided with an eye at the junction of the jaws and with eyes at the outer ends of said jaws, a lever member pivotally engaged at one end 95 with the eye at the junction of the jaws and said lever member being provided at its opposite end portion with an extension engaged with one of the last named eyes, said extension being pivotally engaged with the 100 eye at the outer end of the second jaw, and a yoke member pivotally engaged with the lever member at points inwardly of its connections with the jaws.

2. A fastening device of the character described comprising coacting jaws formed from a single length of material and provided with an eye at the junction of the jaws and with eyes at the outer ends of said jaws, a lever member pivotally engaged at one end 105 with the eye at the junction of the jaws and said lever member being provided at its opposite end portion with an extension engaged with one of the last named eyes, said extension being pivotally engaged with the 110 eye at the outer end of the second jaw, and a yoke member pivotally engaged with the lever member at points inwardly of its connections with the jaws, the extension of the 115 lever member being angularly related to the adjacent portion of said lever member.

3. A fastening device of the character described comprising coacting jaws formed from a single length of material and provided with an eye at the junction of the jaws 125 and with eyes at the outer ends of said jaws, a lever member pivotally engaged at one end with the eye at the junction of the jaws and said lever member being provided at its opposite end portions with an extension en- 130

gaged with one of the last named eyes, said extension being pivotally engaged with the eye at the outer end of the second jaw, a yoke member pivotally engaged with the 5 lever member at points inwardly of its connections with the jaws, and a handle operatively engaged with the yoke member.

4. A fastening device of the character described comprising coacting jaws formed 10 from a single length of material and provided with an eye at the junction of the jaws and with eyes at the outer ends of said jaws, a lever member pivotally engaged at one end with the eye at the junction of the jaws and 15 said lever member being provided at its opposite end portion with an extension engaged with one of the last named eyes, said extension being pivotally engaged with the eye at the outer end of the second jaw, a yoke 20 member pivotally engaged with the lever at points inwardly of its connections with the jaws, the intermediate portion of the yoke member being provided with longitudinally spaced eyes, and a handle pivotally engaged 25 with said eyes.

Copies of this patent may be obtained for five cents each, by addressing the "Commissioner of Patents, Washington, D. C."

5. A fastening device of the character described comprising resilient jaws having their adjacent ends indirectly connected, a lever member pivotally connected at one end to the connected portions of said jaws, the 30 opposite end portion of said lever member being substantially L shape, the outer end portion of one of the jaws being pivotally engaged with the opposite end portion of the lever member, the outer end portion of the second jaw being pivotally engaged with the heel of the L shape portion of the lever member, and a yoke member pivotally engaged with the lever member at points inwardly of the connection between the yoke 35 member and the connected portions of the jaws and inwardly of the heel of the L shape portion of the yoke member.

In testimony whereof I hereunto affix my signature in the presence of two witnesses. 40

HENRY NELSON.
